UNITED STATES PATENT OFFICE.

FRANK VOREL, OF HANOVER, MONTANA.

FIGURE TOY.

Application filed October 5, 1922. Serial No. 592,610.

To all whom it may concern:

Be it known that I, FRANK VOREL, a citizen of the United States of America, residing at Hanover, in the county of Fergus and State of Montana, have invented certain new and useful Improvements in Figure Toys, of which the following is a specification.

This invention relates to certain new and useful improvements in toys and has particular reference to a toy of the figure type wherein a rod or handle having a block slideable thereon and manually operable has a figure toy associated therewith and connected thereto and to said sliding block by link arms causing the figure toy to move from a position adjacent the side of said handle to a position extending transversely of one end thereof.

20 A further object of the invention resides in the provision of a toy of the type above set forth wherein a weighted lever carried by the body portion of the figure toy has one end thereof terminating at the mouth portion of the toy head to be moved to a position spaced from the head when the figure toy assumes a position transversely of the end of the handle simulating the opening of the mouth of the figure toy.

25 With the above general objects in view and others that will appear as the nature of the invention is better understood, the same consists of the novel form, combination and arrangement of parts hereinafter 30 more fully described, shown in the accompanying drawing and claimed.

In the drawing, wherein like reference characters designate corresponding parts throughout the several views,

40 Figure 1 is a side elevational view of the toy showing the toy figure retracted or moved to a position at one side of the handle,

45 Figure 2 is a side elevational view of a figure toy constructed in accordance with the present invention, showing the toy figure positioned transversely of the outer end of the handle and with the mouth portion of the toy figure moved to an open position,

50 Figure 3 is a cross sectional view taken on line III—III of Fig. 1 showing the mouth portion of the toy figure, and

55 Figure 4 is a fragmentary side elevational view showing the operating block for the toy figure slidably mounted upon the handle

rod and the arm connections between the sliding block and the tail portion of the toy figure.

Referring more in detail to the accompanying drawing, there is illustrated a toy figure movably associated with a handle rod, the latter being designated by the reference numeral 1 having a manually shiftable block 2 slideable thereon as shown in Figs. 1 and 2.

60 A toy figure is associated with the outer end of the handle rod 1 and the sliding block 2, the body portion 3 of the toy figure having side links 4 pivoted thereto as at 5, while the opposite ends of said links are 65 pivotally connected as at 6 to the outer end of the handle rod 1, outwardly of the sliding block 2. The tail portion 7 of the toy figure is pivotally connected as at 8 to side arms 9 that are rigidly connected as at 10 70 with the sliding block 2, as clearly shown in Fig. 4.

75 As shown more clearly in Figs. 1 to 3, the body portion 3 of the toy figure and the head 11 thereof are slotted or grooved as 80 at 12 upon the lower side and within which grooves a lever 13 is pivotally mounted as at 14, the outer end of the lever 13 being overbalanced and having a head portion 15 constituting the chin of the head 11 of the 85 toy figure, the contacting edges between the head 11 and chin portion 15 being serrated as at 16 in simulation of an open mouth.

90 In the operation of the device, assuming that the figure toy is in the position shown in Fig. 1, outwardly sliding movement of the block 2 upon the handle rod 1 will shift the toy figure, the link connections 4 between the handle rod and body portion 3 of the toy figure permitting free relative 95 movement of the figure relative to the handle rod, while the arm connections 9 between the block 2 and tail portion 7 of the toy figure causing the rear end or tail portion thereof to be elevated for disposing the toy 100 figure transversely of the outer end of the handle rod 1 as shown in Fig. 2. When the toy figure is so disposed, the outer weighted end of the lever 13 will be lowered, causing the chin portion 15 thereof to be separated 105 from the head 11 of the toy figure in simulation of the opening of the mouth thereof, that portion of the lever 13 designated by the reference numeral 17 representing the tongue of the toy figure.

From the above detail description of the device, it is believed that the construction and operation thereof will at once be apparent, and while there is herein shown and described the preferred embodiment of the present invention, it is nevertheless to be understood that minor changes may be made therein without departing from the spirit and scope thereof as claimed.

10. What is claimed as new is: —

In a figure toy, a handle rod, a block slidably mounted thereon, a toy figure associated with the handle rod and block and embodying link connections between the body portion of the toy figure and the outer end of the handle rod, arms rigidly connected to said block and pivotally connected at

their outer ends to the tail portion of said toy figure, the under side of the toy figure having a cutaway portion adjacent the head and throat of the same, an overbalanced lever within the cutaway portion rearwardly of the head, said lever being of curved formation with one end terminating at the head of the toy figure and a chin member for the head carried by the adjacent end of the lever with the chin member spaced from the head when the toy figure is horizontally positioned and with the exposed portion of the lever simulating the tongue of the toy figure.

In testimony whereof I affix my signature.

FRANK VOREL.
